United States Patent Office

Des. 222,108
Patented Sept. 28, 1971

222,108

DRILL PRESS

Edgar P. Freer, Los Angeles, Calif., assignor to Hubach-Freer Corporation, Woodland Hills, Calif.

Filed May 25, 1970, Ser. No. 23,142

Term of patent 14 years

Int. Cl. D15—99

U.S. Cl. D54—14

FIG. 5FIG. 6FIG. 1 is a perspective view of a drill press, showing my new design;

FIG. 2 is an elevational view thereof as seen from the left side;

FIG. 3 is an elevational view thereof as seen from the right side;

FIG. 4 is a top plan view thereof;

FIG. 5 is a front elevational view thereof; and

FIG. 6 is a rear elevational view thereof.

I claim:

The ornamental design for a drill press, substantially as shown.
